ADJUSTABLE BRACKET

Alfred Peckham, Sturgis, Mich., assignor to
Kirsch Company, Sturgis, Mich.

Application June 29, 1939, Serial No. 281,933

19 Claims. (Cl. 156—19)

This invention relates to improvements in adjustable brackets.

This invention relates to brackets for swinging curtain rods or cranes or for similar curtain rods which are supported at one end only. Heretofore such curtain rods or cranes have been provided with brackets attachable to the wall by means of attaching screws or the like and it has been difficult to place the brackets so as to be sure that when curtains or draperies are hung upon the rods, the rods will be level. Various adjusting means have been employed but have not been entirely satisfactory.

The objects of this invention are:

15 First, to provide a new and improved bracket for swinging curtain rods or the like.

Second, to provide such a bracket which is easily adjustable to level the curtain rod either before or after the drapes or curtains have been hung thereon.

20 Third, to provide such a bracket which may be easily and simply adjusted by means of a screw driver and in which the one adjusting the bracket may position himself out away from the window during the adjusting to simplify the leveling of the curtain rod.

Fourth, to provide such a bracket which is unitary in its nature and which may be inexpensively produced.

30 Other objects and advantages pertaining to details and economies of construction and operation will appear from the description to follow. Preferred embodiments of my invention are illustrated in the accompanying drawing, in which:

35 Fig. 1 is a perspective view of my improved bracket showing in dotted lines how the bracket may be easily adjusted from the front by means of a common screw driver.

40 Fig. 2 is a front face view of a bracket made according to my invention showing in dotted lines the positions to which the bracket may be adjusted.

Fig. 3 is a detail sectional view of the lower portion of my bracket taken on the line 3—3 of Fig. 4.

Fig. 4 is a detail view from the front of the adjusting portion of the bracket, with the cam in section.

50 Fig. 5 is a detail view of the adjusting portion of the bracket, showing a slightly modified form of the invention shown in Figs. 1—4.

Fig. 6 is a detail view of the lower portion of a modified form of the invention showing a slightly different type of adjusting mechanism.

Fig. 7 is a detail sectional view taken on line 7—7 of Fig. 6.

In Fig. 1, I show my improved bracket 1 attached to a window casing or wall 2. I show a swinging curtain rod 3 attached by pivot 4 to the bracket 1, although it will be apparent that my invention is applicable to similar curtain rods supported at one end and not pivoted to the bracket. The bracket is made of sheet metal and the sheet metal base 5 which lies flat against the wall is provided at its upper end with a hole 6 to pivotally receive an attaching screw 7.

The lower portion 8 of the base is slightly offset from the rest of the base and is provided with an elongated slot 9 extending upwardly from the lower end of the bracket. A cam 10 is rotatably disposed in said slot and engages the sides of the slot. The periphery of the cam is provided with a groove 11 into which the edges of the slot fit so that the cam will be retained in the slot, making a unitary bracket structure. The cam 10 is provided with an eccentrically disposed hole 12 to pivotally receive an attaching screw 13. The side of the cam is provided with a slot 14 to receive a screw driver, as shown in dotted lines in Fig. 1, so that the cam may be rotated about the screw 13 as an axis.

I prefer to have the slot 14 extend radially from the hole 12 as shown. In the form of invention shown in Figs. 1—4, the sheet metal of the base 5 is formed to provide ears 15 which, after the cam 10 is placed in the slot, are bent inwardly as shown, so that the cam will not fall out of the slot so that there is a complete unitary structure.

In use my bracket is attached to the wall or window casing by means of the screw 7 extending through the hole 6. The rod is roughly leveled with the cam 10 in the position shown in Fig. 1 and the screw 13 is screwed into place but not completely to position. I prefer to have the screw tight enough to hold the cam in position against the wall or window casing, but not tight enough to prevent turning of the cam by insertion of a screw driver in the slot 14. It may be possible to accomplish the adjustment without tightening the screw 13 to this extent if the frictional engagement between the wall and the base of the bracket is sufficient to momentarily hold the bracket in adjusted position. The final leveling of the bracket is accomplished by making use of a screw driver 15 shown in dotted lines in Fig. 1, which is grasped by the hand 16 of the one adjusting the bracket who may, because of the arrangement of the slot, position 55

himself out in front of the window so as to be able to determine when the bracket has been adjusted to a proper level. This can be accomplished easily when the curtains or drapes are 5 on the rod, so that any sagging caused by the weight of the curtains or draperies can be compensated for during adjustment.

After the proper level has been obtained by adjustment, the screw 13 is tightened so that 10 frictional engagement between the back of the cam 10 and the wall or window casing holds the cam in desired position and thus holds the rod in adjusted position. The upper screw 7 also may be tightened to assist in holding the bracket 15 in position.

In Fig. 5, I show a slightly modified form of the invention. Instead of forming the ears 15 at the bottom of the slot 9 and bending such ears in, I merely deform the metal in a press 20 as indicated at 115, so that the cam 110 cannot slip from the slot. The bracket 105 and cam 110 are otherwise identical, in this form of the invention, with those shown in Figs. 1-4.

In Figs. 6 and 7, I show a further modification 25 of the invention. The lower portion 208 of the bracket 205 is not offset from the wall as in the form of invention shown in Figs. 1-4 or in Fig. 5. The slot 209 is vertically elongated and receives a cam 210 which does not have a peripheral groove. The cam 210 fits in the slot 209 for 30 rotation and is provided with the hole 212 eccentrically located and the slot 214 to receive a screw driver is similar to the slot 14 of the form of invention shown in Figs. 1-4 and functions in 35 the same way. The adjustment of the bracket and the rod is obtained in the same way, but the cam is not held in position to form a unitary structure. The rod is held in adjusted position by having the screw 213 clamp the cam 210 tightly 40 against the wall or window casing.

It will be apparent that one can modify the structure above described without departing from 45 my invention and I do not wish to be limited to the specific form of the invention shown. I have defined the invention in the appended 45 claims.

Having thus described my invention, what I claim as new and desire to secure by Letters Patent is:

1. A bracket for swinging curtain rods or the like having a wall engaging metal base, a hole in the upper portion of said base to pivotally receive a supporting screw or the like, a vertically elongated slot below and extending in a direction substantially radial to said hole and opening to 50 the lower edge of said base, a cam rotatably fitted in said slot and having a peripheral groove engaging the side edges of said slot, an eccentrically disposed hole in said cam to receive an attaching screw or the like, a slot in the side of said cam to receive a screw driver to rotate said cam about the eccentrically disposed hole as an axis, the metal of said base at the lower extremity of said slot being bent to close said slot to retain said cam and provide a unitary structure.

2. A bracket for swinging curtain rods or the like having a wall engaging base, a hole in the upper portion of said base to pivotally receive a supporting screw or the like, a vertically elongated slot below and extending in a direction substantially radial to said hole and opening to the lower edge of said base, a cam rotatably fitted in said slot and having a peripheral groove engaging the side edges of said slot, an eccentrically disposed hole in said cam to receive an attaching 70 screw or the like, a slot in the side of said cam to receive a screw driver to rotate said cam about the eccentrically disposed hole as an axis.

screw or the like, a slot in the side of said cam to receive a screw driver to rotate said cam about the eccentrically disposed hole as an axis, and means to retain said cam in said slot.

3. A bracket for swinging curtain rods or the like having a wall engaging base, a hole in the upper portion of said base to pivotally receive a supporting screw or the like, a vertically elongated slot below and extending in a direction substantially radial to said hole and opening to 10 the lower edge of said base, a cam rotatably fitted in said slot and having a peripheral groove engaging the side edges of said slot, an eccentrically disposed hole in said cam to receive an attaching screw or the like, means on said cam engageable to rotate said cam about the eccentrically disposed hole as an axis, and means to retain said cam in said slot.

4. A bracket for swinging curtain rods or the like having a wall engaging base, a hole in said base to pivotally receive a supporting screw or the like, an elongated slot extending in a direction substantially radial to said hole, a cam rotatably fitted in said slot and having a peripheral groove engaging the side edges of said slot, an eccentrically disposed hole in said cam to receive an attaching screw or the like, a slot in the side of said cam to receive a screw driver to rotate said cam about the eccentrically disposed hole as an axis, and means to retain said cam in 20 said slot.

5. A bracket for swinging curtain rods or the like having a wall engaging base, a hole in said base to pivotally receive a supporting screw or the like, an elongated slot extending in a direction substantially radial to said hole, a cam rotatably fitted in said slot and having a peripheral groove engaging the side edges of said slot, an eccentrically disposed hole in said cam to receive an attaching screw or the like, means on said cam engageable to rotate said cam about the eccentrically disposed hole as an axis, and means to retain said cam in 30 said slot.

6. A bracket for swinging curtain rods or the like having a wall engaging base, a hole in the upper portion of said base to pivotally receive a supporting screw or the like, a vertically elongated slot below and extending in a direction substantially radial to said hole, a cam rotatably fitted in said slot and engaging the sides thereof, an eccentrically disposed hole in said cam to receive an attaching screw or the like, a slot in the side of said cam to receive a screw driver to rotate said cam about the eccentrically disposed hole as an axis, and means to retain said cam in 50 said slot.

7. A bracket for swinging curtain rods or the like having a wall engaging base, a hole in the upper portion of said base to pivotally receive a supporting screw or the like, a vertically elongated slot below and extending in a direction substantially radial to said hole, a cam rotatably fitted in said slot and engaging the sides thereof, an eccentrically disposed hole in said cam to receive an attaching screw or the like, and a slot in 60 the side of said cam to receive a screw driver to rotate said cam about the eccentrically disposed hole as an axis.

8. A bracket for swinging curtain rods or the like having a wall engaging base, a hole in 70 said base to pivotally receive a supporting screw or the like, an elongated slot extending in a direction substantially radial to said hole, a cam rotatably fitted in said slot and engaging the sides thereof, an eccentrically disposed hole in said 75

- cam to receive an attaching screw or the like, a slot in the side of said cam to receive a screw driver to rotate said cam about the eccentrically disposed hole as an axis, and means to retain said 5 cam in said slot.
9. A bracket for swinging curtain rods or the like having a wall engaging base, a hole in said base to pivotally receive a supporting screw or the like, an elongated slot extending in a direction substantially radial to said hole, a cam rotatably fitted in said slot and engaging the sides thereof, an eccentrically disposed hole in said cam to receive an attaching screw or the like, and a slot in the side of said cam to receive a screw 10 driver to rotate said cam about the eccentrically disposed hole as an axis.
10. A bracket for swinging curtain rods or the like having a wall engaging base, a hole in the upper portion of said base to pivotally receive a 15 supporting screw or the like, a vertically elongated slot below and extending in a direction substantially radial to said hole, a cam rotatably fitted in said slot and engaging the sides thereof, an eccentrically disposed hole in said cam to receive an attaching screw or the like, means on 20 said cam engageable to rotate said cam about the eccentrically disposed hole as an axis, and means to retain said cam in said slot.
11. A bracket for swinging curtain rods or the like having a wall engaging base, a hole in said base to pivotally receive a supporting screw or the like, an elongated slot extending in a direction substantially radial to said hole, a cam rotatably fitted in said slot and engaging the 25 sides thereof, an eccentrically disposed hole in said cam to receive an attaching screw or the like, and means on said cam engageable to rotate said cam about the eccentrically disposed hole as an axis.
12. A bracket for swinging curtain rods or the like having a wall engaging base, a hole in said base to pivotally receive a supporting screw or the like, cam following means on said bracket, a cam engaging said cam following means and having an eccentrically disposed hole to receive an attaching screw or the like, and a slot in said cam to receive a screw driver to rotate said cam about the eccentrically disposed hole as an axis 30 whereby the bracket may be leveled.
13. A bracket for swinging curtain rods or the like having a wall engaging base, a hole in said 35 cam to receive an attaching screw or the like, and means to retain said cam in said slot.

base to pivotally receive a supporting screw or the like, cam following means on said bracket, a cam engaging said cam following means and having an eccentrically disposed hole to receive an attaching screw or the like, and means on 5 said cam engageable from in front to rotate said cam about the eccentrically disposed hole as an axis whereby the bracket may be leveled.

14. A bracket for swinging curtain rods or the like having a wall engaging base, a hole in said base to pivotally receive a supporting screw or the like, cam following means on said bracket, a cam engaging said cam following means and having an eccentrically disposed hole to receive an attaching screw or the like, and means on 10 said cam engageable to rotate said cam about the eccentrically disposed hole as an axis whereby 15 the bracket may be leveled.

15. A bracket for swinging curtain rods or the like having a wall engaging base, a hole in said 20 base to pivotally receive a supporting screw or the like, cam following means on said bracket, and a cam engaging said cam following means and having an eccentrically disposed hole to receive an attaching screw or the like.

16. A bracket for swinging curtain rods or the like, cam following means on said bracket, a cam 25 engaging said cam following means and a slot in said cam to receive a screw driver to rotate said cam whereby the bracket may be leveled.

17. A bracket for swinging curtain rods or the like, cam following means on said bracket, a cam engaging said cam following means, and means on said cam engageable from in front to 30 rotate said cam whereby the bracket may be 35 leveled.

18. A bracket for swinging curtain rods or the like, comprising a base, mounting means for pivotally mounting said base on a wall or the like, and adjusting means engageable from in front for adjusting said base about the pivot of said mounting means comprising a slot to receive a screw driver.

19. A bracket for swinging curtain rods or the like, comprising a base, mounting means for pivotally mounting said base on a wall or the like, and adjusting means engageable from in front for 45 adjusting said base about the pivot of said mounting means.

ALFRED PECKHAM. 50
